GAS BURNER

Application filed November 30, 1928. Serial No. 322,778.

Our invention relates to gas burners, more particularly to burners for use in furnaces and has for its object the provision of a device of the character designated wherein an improved mixture of air and gas for combustion is provided.

A further object of our invention is to provide a gas burner of the type wherein air for combustion is entrained in a flowing gas stream, and wherein pneumatic means is provided for effecting a more intimate mixture of the air and gas.

Briefly, our invention is an improvement on a well known type of gas burner wherein the gas for combustion under suitable head is passed through a converging-diverging nozzle which is open to the atmosphere at the throat so that air for combustion is entrained by the flowing gas. While such burners are in wide use and satisfactory results are obtained therewith, we have found that markedly improved results may be obtained and much higher temperatures attained in the furnace for a given gas consumption by increasing the intimacy of the gas-air mixture. We accomplish this result by means of jets of air from a suitable source of air under pressure which cut the flowing mixture of gas and air in a direction having a radial component of motion. This action creates a turbulence in the air-gas stream whereby a most intimate mixture is effected. We have found, with our improved apparatus, that furnace temperatures which are 500° F. higher can be obtained than can be obtained with the same burner and without our improved means for perfecting the air-gas mixture, all with the same or less gas consumption.

Apparatus embodying features of our invention is illustrated in the accompanying drawings, forming a part of this application, wherein

Fig. 1 is a view in elevation showing our improved burner assembled with a furnace;

Fig. 2 is a view in front elevation of our improved mixing device in association with the gas nozzle; and

Fig. 3 is a sectional view taken along the line III—III of Fig. 2.

Referring to the drawings for a better understanding of our invention, we show a fragment 10 of a furnace wall having an opening 11 therein for receiving a mixture of gas and air for combustion and which is supplied to the opening through a conduit 12.

The conduit 12 diverges at its outer end to provide an intake 13 for gas and air for combustion. Formed or secured on the outer end of the intake 13 is a frame 14 through which extends a gas nozzle 16 which is in axial alignment with the conduit 12 and which terminates at 17 a slight distance within the intake 13. The nozzle 16 is connected to a gas supply conduit 18 through which gas under suitable pressure is supplied to the apparatus.

Fitting within the end of the nozzle 17 is a nozzle tip 20 having a diverging opening 19 into the gas nozzle 17. The function of the tip 20 is to direct a high velocity jet of gas into the conduit 12 which entrains with it air from the atmosphere drawn into the open divergent end of the intake 13.

The nozzle 17 is provided with exterior threads 21 and fitting around the nozzle in threaded engagement therewith is a knurled collar 22 having a hub portion 23. Loosely fitting over the hub portion 23, so as to be easily turnable with respect thereto, is a hollow annular member 26 provided with a threaded opening 27 to which is connected a conduit 28 for supplying the annular chamber with air under suitable pressure. The front face of the hollow member 26 is drilled to provide a plurality of small converging openings 29, said openings being so arranged as to direct a plurality of jets of air into the stream of gas and air entering the intake 13. The hollow member 26 is held in place on

the hub portion 23 by means of a ring 25 which is brazed or otherwise secured to the hub portion.

The operation of our improved apparatus will be apparent. When gas under pressure is supplied to the nozzle 17 and escapes through the nozzle tip 20 in a high velocity jet, it entrains the air from the atmosphere into the intake 13 and delivers it through the opening 11 into the furnace for combustion. At the same time air under suitable pressure is supplied to the hollow member 26 through the conduit 28 and escapes from the converging openings to strike the mixture of air and gas in the intake 13 with a radial component of motion, thereby cutting the air-gas stream at a plurality of points and forcing it into a thorough and intimate mixture. The position of the hollow member 26 with respect to the nozzle may be varied by turning the knurled nut 22 to advance or retard it with respect to the nozzle tip 20.

While the air and gas pressures employed with our improved burner might vary with varying conditions under which combustion is to occur and with varying qualities of gas, we have been enabled to attain maximum furnace temperatures with a 3 pound gas pressure and with a 2 pound air pressure in the hollow member 26. In careful tests which we have carried out with our apparatus, the temperatures thus attained were around 500° F. higher than where the burner was employed without cutting the air-gas mixture with jets of air.

From the foregoing it will be apparent that we have devised an improved gas burner which is simple of construction and operation and which is capable of effecting a highly improved mixture of air and gas for combustion.

While we have shown our invention in but one form, it will be obvious to those skilled in the art that it is not so limited but is susceptible of various changes and modifications without departing from the spirit thereof and we desire therefore that only such limitations shall be placed thereupon as are imposed by the prior art or as are specifically set forth in the appended claims.

What we claim is:

1. In a gas burner, a conduit having a divergent opening, a gas nozzle in axial alignment with the conduit and adapted to discharge a gas stream into the opening, means for discharging a plurality of air jets each having a radial component of motion into the opening and crossing the gas stream, and means to vary the origin of the air jets axially of the gas stream.

2. In a gas burner, a conduit having a divergent opening, a gas nozzle in axial alignment with the conduit and adapted to discharge a gas stream into the opening,

means defining an annular chamber surrounding the gas nozzle and provided with a plurality of openings in the front face thereof, said openings converging toward the discharge end of the gas nozzle, means for supplying air under pressure to the annular chamber, and means for adjusting the position of the annular chamber axially of the gas nozzle.

In testimony whereof we affix our signatures.

THEODORE H. CREMER.
JAMES D. CARLIN.
